TUBE FOR TOOTH PASTE

Filed May 26, 1930

Willoughby N. Offley.
Inventor

By *W. L. Simmons*
Attorney

raised position the cap and bail may be swung away from the discharge opening of the tube, and the contents of the tube dispensed. When the cap is to be closed, it is moved from 5 the position shown in Figures 6 and 8 to the position shown in Figures 4 and 5 and then pressed downwardly over the end of the discharge neck where it is held firmly in position. When in this position the upper end of 10 the bail 16 may be used as a loop to suspend the tube, as by passing the upper end of the bail over a nail, hook, or the like.

Due to the absence of screw threads the 15 operation of the cap is very simple. The tube may be held in the palm of the hand and the cap grasped by the thumb and index finger of the hand holding the tube and moved upwardly and away from the discharge opening. It will be seen then that the cap may 20 be operated by the use of but one hand, and that the cap cannot be lost or misplaced due to the pivoted bail. The shoulders 18 firmly hold the cap in position and prevent the escape of the contents of the tube.

25 While I have shown and described the preferred embodiment of my invention, it is to be understood that various changes in the size, shape, and arrangement of parts may be resorted to without departing from the spirit 30 of my invention or the scope of the subjoined claims.

Having thus described my invention, what I claim and desire to protect by Letters Patent is:

35 1. The combination with a tube having a discharge neck, of a closure comprising a cap having a greater diameter than the neck of the tube, said cap having guide recesses therein, a bail having arms extending through 40 said recesses in the cap and secured to the neck of the tube, the arms of the bail being provided with resilient projections adapted to engage the top of the cap when in its closed position, said cap being adapted to be moved 45 past said projections to clear the neck of the tube.

2. The combination with a containing tube having a discharge neck, of a closure comprising a cap having a greater diameter than 50 the neck of the tube, said cap having a longitudinal guide opening therein, a guide member pivoted to the neck of said tube at a point spaced from the top thereof, said guide member extending through the opening in the cap 55 and a substantial distance thereabove, means to prevent the removal of the cap from the guide member, and a resilient projection on said guide member intermediate of its ends and adapted to engage the cap in the closed 60 position thereof, said cap being adapted to be moved past said projection to clear the neck of the tube.

3. The combination with a containing tube having a discharge neck, of a closure comprising a cap having a greater diameter than 65

the neck of the tube, said cap having a recess therein adapted to receive the neck of the tube, said cap being provided with a pair of guide openings arranged at substantially diametrically opposite points adjacent the periphery thereof, a spring wire bail having arms extending through the openings in the cap and pivotally secured to the neck of the tube at a point spaced from the top thereof, said bail being widest at a point intermediate of its ends, the widest portion of the bail being arranged above the cap when the cap is in its closed position.

4. The combination with a tube having a discharge neck of a closure comprising a cap having a greater diameter than the neck of the tube, said cap having a recess therein adapted to receive the neck of the tube, and said cap having a pair of longitudinal guide openings therein arranged at substantially diametrically opposite points adjacent the periphery thereof, a spring wire bail having arms extending through the openings in the cap and pivotally secured to the neck of the tube, the arms of said bail being crimped intermediate of their ends to form projecting shoulders adapted to engage the top of the cap in the closed position of the cap.

5. The combination with a tube having a discharge neck, of a closure comprising a cap having a pair of longitudinally extending guide openings therein arranged at substantially diametrically opposite points, a spring wire bail having arms extending through the openings in the cap and pivotally secured to the neck of the tube, the arms of said bail being crimped intermediate of their ends to form projecting shoulders adapted to engage the cap in the closed position thereof.

6. The combination with a containing tube, 105 of a closure comprising a cap having a pair of longitudinally extending guide openings arranged at substantially diametrically opposite points, a spring wire bail having arms extending through the openings in the cap and pivotally secured to the tube, the arms of said bail being crimped intermediate their ends to form projecting shoulders adapted to engage the cap in the closed position thereof, 110 said arms converging downwardly below said shoulders and converging upwardly above said shoulders.

7. The combination with a tube having a discharge neck, of a closure comprising a cap having a recess therein to receive the neck of the tube, said cap having longitudinally extending openings arranged therein at substantially diametrically opposite points, a spring wire bail having arms extending through the openings in the cap and turned in at their ends to form studs which fit into sockets in the tube neck, the openings in the cap being of substantially greater diameter than the diameter of the bail arms, the arms of said bail being crimped intermediate their 125

ends to form projecting shoulders adapted to engage the top of the cap in the closed position thereof, said arms converging downwardly below said shoulders and converging 5 upwardly above said shoulders.

8. The combination with a container having a discharge neck, a spring wire bail pivotally secured to said discharge neck below the top thereof, said bail being wider adjacent its upper end than at its lower end, a cap for said discharge neck, said cap having longitudinally arranged openings therein to receive the arms of said bail and to slide thereon, the wide upper end of the bail being 10 adapted to receive and support the cap in the raised position of the cap.

9. The combination with a container having a discharge neck, a spring wire bail pivotally secured to said discharge neck below the top thereof, said bail being wider adjacent its top than at its lower end, a cap for 20 said discharge neck, said cap being provided with longitudinally arranged guide openings of substantially greater diameter than the arms of the bail and adapted to receive the 25 arms of the bail and to slide thereon, the wide upper end of the bail being adapted to receive and support the cap in the raised position of the cap.

10. A container closure comprising a cap having a longitudinal guide opening therein, a guide member adapted to be secured to a container and extending through the opening in the cap and a substantial distance there- 35 above, and a resilient projection on said guide member intermediate its ends and adapted to engage the cap in the closed position thereof, said cap being adapted to be moved past said projection to clear the top of the container.

40 In testimony whereof I affix my signature.
WILLOUGHBY NEWTON OFFLEY.
